UNITED STATES PATENT OFFICE.

SAMUEL W. LEWIS, OF BROOKLYN, NEW YORK, ASSIGNOR TO LEWIS-IUDEX CO., OF BROOKLYN, NEW YORK, A CORPORATION OF NEW YORK.

DESIGN FOR A VALVE-BODY.

45,841.

Specification for Design.

Patented May 26, 1914.

Application filed March 19, 1914. Serial No. 825,920. Term of patent 14 years.

To all whom it may concern:

Be it known that I, SAMUEL W. LEWIS, a citizen of the United States, residing in the borough of Brooklyn, in the county of Kings, city and State of New York, have invented a new, original, and ornamental Design for a Valve-Body, of which the following is a specification, reference being had to the accompanying sheet of drawings, forming a part of this specification, in which—

Figure 1 is a perspective front view of that part of a flushing valve body which embodies the three essential features of my ornamental design. Fig. 2 is a reduced side view of the same.

As shown in the drawing, particularly in Fig. 1, the leading and essential feature of

this design is a valve body composed of three sections or parts placed one above the other. The lower section or part A is surmounted by the middle section forming an enlargement or bead provided with a knurled or roughened surface or band B on its periphery and above that a cylindrical extension forming the third section and being also provided with a peripheral band C having a knurled or roughened surface as shown in the drawings.

I claim—

The ornamental design for a valve body as herein shown and described.

SAML. W. LEWIS.

Witnesses:

J. J. VETTER,

EDWARD DEZURKE.
